UNITED STATES PATENT OFFICE.

WILFRED L. GUERIN, OF NEW ORLEANS, LOUISIANA, ASSIGNOR OF ONE-HALF TO
MORINVILLE J. GUERIN, JR., OF NEW ORLEANS, LOUISIANA.

INDICATOR FOR VACANT THEATER SEATS.

Application filed December 23, 1921. Serial No. 524,431.

To all whom it may concern:

Be it known that I, WILFRED L. GUERIN, a citizen of the United States, residing at New Orleans, in the parish of Orleans and State of Louisiana, have invented certain new and useful Improvements in Indicators for Vacant Theater Seats; and I do hereby declare the following to be a full, clear, and exact description of the invention, such as will enable others skilled in the art to which it appertains to make and use the same.

This invention relates to a means for indicating the vacant seats in a theater, and has for its object to provide a mechanism which will be comparatively inexpensive to construct and more efficient in use than those heretofore proposed.

With these and other objects in view, the invention consists in the novel details of construction and combinations of parts more fully hereinafter disclosed and particularly pointed out in the claims.

Referring to the accompanying drawings forming a part of this specification, in which like numerals designate like parts in all the views:

Figure 1 is a diagrammatic, perspective view of the outside of an indicator made in accordance with this invention;

Figure 2 is a partially sectional view of the parts shown in Figure 1, illustrating the interior mechanism;

Figure 3 is a cross sectional view taken on the line 3—3 of Figure 2, looking in the direction of the arrows;

Figure 4 is a perspective view partially broken away, of two of the conducting bars forming a portion of the circuits;

Figure 5 is a perspective view of a portion of the contact closing members;

Figure 6 is a detail view illustrating the connection at the lamp sockets; and

Figure 7 is a diagrammatic view illustrating one of the lamp circuits.

1 indicates any suitable supporting means, preferably of a box like form, 2 a means such as a strap for carrying the box 1 on the person, 3 a battery or other source of current carried in the box 1, 4 one pole of the battery 3, 5 the other pole or terminal of the battery 3, 6 a connection between the terminal 5 and the hinge member 7 on which are pivotally mounted a series of depressible contact members 8, 9 a plurality of contacts

adapted to be pressed upon by the members 8 when circuit is to be made, 10 a plurality of connections from the contacts 9 to the conducting bar 11, one for each contact 9, 12 a plurality of connections from the conducting bar 11 to the return conducting bar 13, and 14 a return wire from the conducting bar 13 to the terminal 4, as shown. The wires 10 lead to the usual contacts for the series of lamps 16, the sockets of which are in electrical contact with the conducting bar 11, all as will be clear from Figures 4 and 6.

Accordingly, for the particular row of circuit closers 8 and contacts 9, the current will flow as follows:

From the terminal 5 of the battery through the wire 6, through the hinge member 7, the depressible contact makers 8, the contacts 9, through the wires 10, through the contacts 17 of the lamp sockets carried by the bar 11 through the wires 12, the return bar 13, the wire 14, and back to the terminal 4 of the battery, all as will be clear from Figures 2, 3, 4, 6 and 7.

In addition to the row of circuit makers 8, there is a duplicate row of circuit makers 20, provided with a hinge member 21, and each in all respects a duplicate of the contact makers 8, on hinge member 7; and current flows from the terminal 5 of the battery 3 through the wire 22 to said hinge member 21, through the contact makers 20, through the plurality of contacts 23, through the wires 24, one for each contact 23, to and through the lamps 25 carried by the bar 30, through the wires 26 to the return conductor 13, and through the wire 14 back to the terminal 4 of the battery, all in the manner precisely similar to the first mentioned circuit and series of lamps 16.

Each of the contact makers 8 and 20 are provided with a spring 28, see Figure 5, which normally prevents them from making circuit with their corresponding contacts 9 or 23, as the case may be, so that the circuit is normally broken at each circuit maker 8 or 23. On the other hand, each circuit maker 8 and 23 is provided with an insulated right angular extension 29, see Figure 5, which overlies the main body portion of the preceding circuit maker, so that when a circuit maker 8, for example, which may be the second in the row, is depressed, it will not only make circuit at its own second contact 9, but it will also, through the exten-

sion 29, depress the preceding circuit maker 8, and cause it to make circuit with its corresponding contact 9. The result is that both the first and second lamps 16 in the 5 upper series of lamps will be lighted. In the same way, if circuit breaker number three of said series is depressed it will light its own lamp number three as well as lamps numbers two and one. If circuit maker 10 number four in the series of circuit makers 8 is depressed, all of the first four lamps will be lighted, and the same is true of the second row of circuit makers 23.

Now, the row of lamps 16 are adapted to 15 register with the row of holes 32 in the box 1, and to show white lights while the row of lamps 25 are adapted to register with the row of holes 33, see Figure 1, and to show red lights.

20 The operation of this invention will be better understood when it is said that in moving picture theaters it is now customary for the usher to step down the aisle to locate vacant seats while another usher holds back 25 the waiting patrons. The first usher after finding the vacant seats either will return to the head of the aisle and inform the patrons of such vacancies and lead them down to said vacant seats or he will endeavor to 30 signal with his fingers or otherwise to the patrons or to the usher holding said patrons back just how many seats are vacant. This system, however, is slow, cumbersome, and expensive in that it wastes time and re- 35 quires a greater force of ushers than are really necessary. With the device above disclosed, however, the seating of the patrons is greatly facilitated without necessitating the usher searching the rows of seats to 40 signal the other usher or to lose time in returning to the head of the aisle to inform the waiting patrons.

That is to say, with this new device or 45 indicator carrying a row 32 of white lamps and a row 33 of red lamps and hung over the usher's shoulder or supported from his waist, the usher steps down the aisle, locates the vacant seats and then by merely turning and facing the other usher or patrons, 50 he signals the number of seats vacant, and also whether they are single separated seats or whether in pairs or triplets, etc. That is to say, suppose that the red 55 lights will indicate only single seats and that the white lights indicate combinations of seats, that is, doublets, triplets, etc., then the operator or usher in order to indicate to the head of the aisle that there are three 60 single seats available, will press circuit closer number three in the row of circuit makers 23, which control the red lights 25 shining through the series of holes 33. This will cause three red lights to be shown in the 65 row 33 and the patrons or the usher at the head of the aisle will know that there are

three single seats vacant in the row of seats which the operating usher indicates. Should the operating usher wish to indicate that there are four single separated seats in said row, or in some other row, he would indicate by standing opposite or pointing to the row of seats and also would cause four red lights to be lighted in the row of holes 33, by depressing circuit maker number four of the row 23. On the other hand, should the 70 operating usher wish to indicate that pairs of seats or groups of three seats or of four seats are available, in any particular row of seats, he would stand opposite that row of seats and cause only white lights to appear 75 in the row of holes 32.

For example, should he wish to indicate that pairs of seats or doublets, are vacant, he would press key number two, in the row of circuit breakers 8, and it would cause two 80 white lights to appear in the row of holes 32. If he wished to indicate a group of three seats together, he would press key member 3 in the row of circuit makers number eight; for a group of four seats he would 85 press number four in the row of circuit makers number 8, etc. In all cases the usher at the head of the aisle would know exactly how many persons to conduct to the particular row of seats or in case the patrons themselves 90 are familiar with the signals they would find their own seats without any extra usher.

It is obvious that those skilled in the art 95 may vary the details of construction as well 100 as the arrangement of parts without departing from the spirit of the invention, and therefore I do not wish to be limited to the above disclosure except as may be required by the claims.

105 What I claim is:

1. In a vacant seat indicator for theaters, the combination of a plurality of electric lamps constituting a signal to designate a plurality of separated vacant seats; a second 110 set of electric lamps constituting a second signal to designate vacant seats that are not separated from each other; normally open circuits for each lamp; and circuit closers provided with means for operating each other and to close said circuits, whereby upon operating a single circuit closer of said first named signal a plurality of separated 115 vacant seats may be simultaneously indicated, and by operating a single circuit closer of said last named signal a plurality of seats not separated from each other may be simultaneously indicated.

2. In a vacant seat indicator the combination of a set of electric lamps of one color 120 constituting a means for simultaneously designating a plurality of separated vacant seats; a second set of electric lamps of another color constituting a means for designating a plurality of vacant seats not sep- 125

arated from each other; a normally open circuit for each lamp; a circuit closer for each circuit; and a plurality of means associated with said circuit closers by which 5 upon the operation of a single circuit closer in each set a plurality of lamps in each set may be lighted.

3. In a vacant seat indicator the combination of a set of electric lamps of one color 10 constituting a means for simultaneously designating a plurality of separated vacant seats; a second set of electric lamps of another color constituting a means for designating a plurality of vacant seats not sep- 15 arated from each other; a normally open circuit for each lamp; a pivoted circuit closer for each circuit; and a plurality of means comprising overlying extensions associated with said circuit closers by which 20 upon the operation of a single circuit closer in each set a plurality of lamps in each set may be lighted.

4. In a vacant seat indicator the combination of a set of electric lamps constituting a 25 means for simultaneously designating a plurality of separated vacant seats; a second set of electric lamps constituting a means for designating a plurality of vacant seats not separated from each other; a normally

open circuit for each lamp; a circuit closer 30 for each circuit; means for insulating a plurality of said circuit closers from each other; and a plurality of means comprising overlying extensions associated with said circuit closers by which upon the operation of a 35 single circuit closer in each set a plurality of lamps in each set may be lighted.

5. In a vacant seat indicator the combination of a set of electric lamps constituting a means for simultaneously designating a 40 plurality of separated vacant seats; a second set of electric lamps constituting a means for designating a plurality of vacant seats not separated from each other; a normally open circuit for each lamp; a circuit closer 45 for each circuit; hinge members upon which said circuit closers are pivoted; means for insulating a plurality of said circuit closers in each set from each other; and a plurality of means comprising extensions 50 adapted to contact with said insulating means associated with said circuit closers by which, upon the operation of a single circuit closer in each set a plurality of lamps 55 in each set may be lighted.

In testimony whereof I affix my signature,

WILFRED L. GUERIN.
